UNITED STATES PATENT OFFICE.

FRANK L. HARMON, OF BEVERLY, MASSACHUSETTS.

MACHINE FOR SKIVING AND FOLDING LEATHER.

No. 12,535.

Specification of Reissued Letters Patent.

Reissued Oct. 2, 1906.

Original No. 731,566, dated June 23, 1903. Application for reissue filed April 5, 1905. Serial No. 254,060.

To all whom it may concern:

Be it known that I, FRANK L. HARMON, residing at Beverly, in the county of Essex and Commonwealth of Massachusetts, have invented a new and useful Machine for Skiving and Folding Leather, of which the following is a specification, reference being had to the accompanying drawings.

The object of my invention is to provide a machine for producing a folded edge of a piece of leather; and this invention consists in the novel combinations resulting from the combination of means whereupon a piece of leather may be beveled at its edge, and means whereupon the means for beveling may be sharpened, and means whereupon a piece of leather may be slit at intervals at its edge, and means whereupon cement may be put upon the leather, and means whereupon the beveled part of the leather may be folded, and means whereupon the folded part may be pressed, and means whereupon all of the aforesaid means may operate upon the leather in proper order and form a folded edge upon the leather a predetermined distance.

A machine in which this invention is embodied is comprehensively shown in the accompanying drawings, and the especial features and novel combinations of parts and other novelties will hereinafter appear and be fully set forth and described, and claimed in the claims appended hereto.

In the accompanying drawings, Figure 1 is a top plan view of the machine embodying this invention. Fig. 2 shows a cross-sectional elevation on line $z z$, indicated by an arrow at the left-hand corner of Fig. 1. Fig. 3 shows a longitudinal sectional elevation on line $y y$, indicated also by an arrow at the left-hand corner of Fig. 1. Fig. 4 is a perspective detail view of a feeding device, and Figs. 5, 6, 7, and 8 show perspective detail views of devices whereupon the feeding device is yieldingly supported and whereupon the feeding device may be manually adjusted or moved and secured at any necessary angle to the cutting edge of a rotatory disk skiving-knife, leaving the feeding device operative, thereby operatively holding the part of the feeding device which moves the leather at any necessary angle to the rotatory disk skiving-knife, so that the piece of leather may be skived at the edge of said leather at any necessary angle. Fig. 9 shows a vertical section of a device by which a piece of leather is folded so as to form a folded edge and is rubbed

in a direction inward from said folded edge in operative connection with a part of a cement-receptacle and devices connected therewith, whereupon a proper amount of cement is in practice taken out of said cement-receptacle. Fig. 10 shows the construction of a rod and a sleeve thereon whereupon the feeding device is moved in practice. Fig. 11 shows a vertical section of a wheel whereupon a grinding device is rotated in practice for grinding a rotatory disk skiving-knife. Fig. 12 is a perspective view of a gas-burner for heating the device for rubbing the folded part of a piece of leather in a direction inward from the folded edge. Fig. 13 shows a perspective view of a cement-receptacle and devices connected therewith, whereupon a specific or proper amount of cement is in practice automatically taken out of said cement-receptacle. As certain parts by which cement is automatically deposited upon a device for rubbing the cement upon the skived part of the leather after the cement is automatically taken out of said cement-receptacle are obscured by many lines in Fig. 1, a detail plan of said parts is shown in Fig. 14 free from obscuring lines, in order that a comprehensive idea may be conveyed as to their construction and operation. Fig. 15 is a sectional detail, in side elevation, free from obscuring lines, to more fully illustrate the parts shown in Figs. 3, 1, and 14. Fig. 16 shows an end elevation of some of the parts shown in detail in Figs. 14 and 15 and also illustrates more fully than other views how that a cover for covering the device for rubbing the cement upon the leather is secured to the frame of the machine. Fig. 17 is a sectional detail view in elevation to illustrate the construction of a brush or device for depositing the cement upon the device for rubbing it upon the skived part of the leather.

In the journal-bearings of the knife-shaft support A^{22} , (shown in Figs. 1, 2, and 3,) rigidly but adjustably secured to the frame A^3 , as and for the purpose hereinafter described, the rotatory disk skiving-knife shaft A^{20} (shown in Figs. 3 and 2) is journaled. The horizontal grooved wheel A^{21} (shown in Figs. 3 and 2) is secured upon said rotatory disk skiving-knife shaft A^{20} . A round belt (not shown) operating in practice in the groove of the wheel A^{21} rotates said wheel A^{21} , the rotatory disk skiving-knife shaft A^{20} , secured thereto, and the rotatory disk skiving-knife A^{17} , secured to said shaft, with great rapid-

ity. Attention is called to the fact that the power conveyed by this belt is exclusively applied to said wheel, knife-shaft, and knife, or, in other words, the knife-shaft is thereby operated independent of the means for conveying power to other parts of the machine. Said wheel, knife-shaft, and knife are rotated independent of the power conveyed to the other parts of the machine, which comprise devices whereupon feeding, cementing, slitting, folding, heating, and rubbing are accomplished in order that it may be possible to raise the speed of the wheel A²¹, knife-shaft A²⁰, and knife A¹⁷ to any desired speed from its normal speed to facilitate the skiving of some kinds of leather properly without affecting the speed of the rest of the operative devices of the machine, and a construction whereupon this could be accomplished not having been heretofore made the combination of means for rotating the knife-shaft and skiving-knife independent of the power conveyed to other operative parts of a skiving-machine in combination with the other operative parts of a skiving-machine in order that the speed of the knife may be raised without affecting the speed of the other operative parts of the machine is of my invention.

On the left-hand side of the frame or box A², (shown in section in Fig. 3,) which box incloses the greater part of the operative mechanism of the machine, is the bracket A', secured to the frame or box A² on the outside of the frame or box by two screws, one above the other, and said bracket extends toward the left at right angles to the frame or box A² outside of the frame. This bracket is peculiar in shape, the lower end thereof being the journal-bearing shown inside of the frame or box A² near the left-hand lower corner of Fig. 3, in which journal-bearing the shaft A is journaled, and the upper end of said bracket being the journal-bearing directly above the first-named journal-bearing, also inside of the frame or box A², in which last-named journal-bearing the shaft A is also journaled. Upon the top of the shaft A above the last-named journal-bearing the device A⁴ for folding and rubbing the skived part of the leather is rigidly secured and is rotated in practice with said shaft. This device A⁴ is shaped like a disk and is beveled, as is shown in Fig. 9, in which figure the device A⁴ is shown in vertical section. Attention is called to the left-hand side of Fig. 1 to the outer circular line which describes the circumference of said device A⁴ in order that a comprehensive idea of the size of this device may be conveyed. Attention is also called to the left-hand upper corner of Fig. 2, at which place in said figure the device A⁴ (shown in elevation) is not obscured by lines, and attention is also called to the right-hand lower corner of Fig. 14, where the device A⁴ is shown in plan, free from obscuring lines,

and attention is also called to the right-hand upper corner of Fig. 15, in which figure the device A⁴ is shown in section and is also shown secured to a part of the shaft A. Attention is again called to the left-hand side of Fig. 3, where the horizontal grooved wheel A³ is shown secured to the shaft A. A round belt (not shown) operating in practice in the groove of said wheel A³ rotates said wheel A³, the shaft A, shown secured thereto, and the device A⁴, shown secured to said shaft and for folding and rubbing the skived part of a piece of leather, and to which device attention has been called in the several views.

Upon the shaft A, inside of the frame or box A² at the left-hand lower corner of said frame, the eccentric or cam A⁵ is shown rigidly secured to the shaft A, which eccentric or cam is rotated by the shaft A when the shaft A is rotated. Immediately above said eccentric or cam A⁵ is shown the coil-spring A⁹, one end of which is secured to a screw shown fast in the bracket A' and the other end of which is secured to a screw shown fast in the sleeve A¹², which sleeve is shown fast to the rod A⁶, which sleeve and rod are shown in detail in Fig. 10, shown below Fig. 3, and as said rod A⁶ is movably supported in the slideways A⁷ and A⁸, fast to the lower part of the frame A², the coil-spring A⁹ moves said rod in practice and forces the left-hand end of said rod (shown also in Fig. 10) against the cam or eccentric A⁵. Therefore it is plain that the rod A⁶ is moved in practice toward the right in the slideways A⁷ and A⁸ against the stress of the spring A⁹ by the eccentric or cam A⁵ when the eccentric A⁵ is rotated by the upright shaft A and is moved in practice toward the left by the force of the spring A⁹, which spring A⁹ moves said rod A⁶, and thereby forces the left-hand end of said rod to follow the face of the eccentric or cam A⁵, the cam and spring imparting a vibratory motion to said rod and the sleeve A¹² secured thereto. The distance that the rod A⁶ is vibrated may be governed by manually adjusting the check-nuts A¹⁰ and A¹¹ on the right-hand end of said rod and outside of the frame A², or, in other words, manually moving and securing them in a position nearer the frame or box A² shown in section near to said check-nuts, thereby preventing said coil-spring A⁹ from moving the rod A⁶ any farther than the distance between the frame and said check-nuts, thereby preventing the left-hand end of said rod from following the face of said cam throughout the movement of said cam, and thereby not allowing the cam A⁵ to move said rod A⁶ the full extent of the throw of the cam. The material or leather is moved in practice intermittently or step by step to the skiving-knife and the folding and rubbing device, as and on account of devices hereinafter described operated by power conveyed through said rod A⁶. Therefore it is plain

that said material or leather to be skived may be caused to be moved intermittently a greater or less distance by adjusting said check-nuts upon said rod A⁶, as hereinabove described. The construction and assembling of all of the devices whereupon the feeding is accomplished except said rod A⁶ and said means whereupon said rod is moved in practice, as aforesaid, are described as follows:

10 The feeding device A¹⁶ (shown in Fig. 4, which figure is shown below Fig. 1) is movably supported in practice between the prongs of the device A²⁷, (shown in Fig. 5, which figure is shown at the right of Fig. 4,) 15 the pin A²⁸ (shown in the right-hand upper corner of Fig. 3) being inserted in the holes shown in the prongs of the device A²⁷ and extending through the hole in the center of the feeding device A¹⁶, said pin fitting loosely in 20 the hole in said feeding device A¹⁶ in the manner shown in Fig. 3. The right-hand round part of the device A²⁷ is inserted in the hole in the sleeve A²⁸, as shown in Figs. 1 and 3, said round part fitting loosely in said hole, which 25 sleeve A²⁸ is shown near to the end of the device A²⁷, and the device A³⁰ (shown in Fig. 7 at the right of the device A²⁸) is secured upon the round part of the device A²⁷ by the screw A³¹, (shown in the device A³⁰,) as shown in 30 Figs. 1 and 3, said device A³⁰ having the function of a collar and having a handle thereon, and the trunnions A³² and A³³ of the sleeve A²⁸ are placed in the round holes shown in the bracket A³⁴, which bracket is made fast to 35 the frame A² on the outside of the frame, the part A²⁷ (shown in Fig. 5 below Fig. 1) and the feeding device A¹⁶, movably secured to said part, extending through the frame A² on the inside of the frame A², as shown in the 40 right-hand upper corner of Fig. 3.

It will be observed by the description of the assembling of the parts whereupon the feeding is accomplished that the trunnions A³² and A³³ of the sleeve A²⁸, movably supported in the round holes shown in the bracket A³⁴, (shown in Fig. 8,) form a construction whereupon the feeding device A¹⁶ (shown in Figs. 3 and 1) may be moved up and down. In order to prevent this feeding 45 device A¹⁶ (shown in the right-hand upper corner of Fig. 3) from falling and turning, the trunnions A³² and A³³ (shown in Fig. 6 under Fig. 1) in the round holes in the bracket A³⁴, (shown in Fig. 8,) in which they are pivoted, 50 as shown in Fig. 3, and that the feeding device A¹⁶ may be yieldingly supported, the spring A⁴⁴ is devised. The spring A⁴⁴ is secured to the part A⁴⁰, which part A⁴⁰ is pivoted by the screw A⁴¹ to the bracket A³⁹, 55 which screw A⁴¹ fits loosely in a hole in said part A⁴⁰ and is firmly secured into the bracket A³⁹ which bracket is fastened to the outside of the frame A² by the screw A⁴², said bracket extending through the frame A², and said 60 spring A⁴⁴ bears against the device A²⁷, in

which the feeding device A¹⁶ is movably secured, and the screw A⁴³ is threaded in the frame A² and forced against the part A⁴⁰, exerting force upon the spring A⁴⁴, thereby causing said spring to hold the feeding device 70 A¹⁶ in the position in which it is shown, and the screw A⁴³ is secured in position by the check-nut thereon. The spring A⁴⁴ is prevented from forcing the feeding device A¹⁶ too high by the screw A⁴⁵, threaded in the 75 right-hand upper corner of the frame A² and extending down vertically and bearing against the device A²⁷, by which device A²⁷ the feeding device A¹⁶ is movably supported. Therefore it is plain that on account of the devices described and the spring A⁴⁴, whereupon the feeding device A¹⁶ is held upward, the feeding device A¹⁶ is yieldingly supported, or, in other words, it may be pushed downward, causing the spring A⁴⁴ to yield, which spring 80 exerts force, whereupon the feeding device A¹⁶ is normally held in its proper elevation or in the elevation in which it is shown. It is also plain that the device A²⁷ may be manually turned or adjusted in the hole in the 85 sleeve A²⁸ by the handle of the device A³⁰ (shown in Figs. 7, 3, and 1) and secured by the screw A²⁹ in the sleeve A²⁸, (shown in Figs. 6, 3, 2, and 1,) thereby adjusting the feeding device A¹⁶, movably supported in the 90 device A²⁷, as hereinabove described and as shown in Figs. 5, 3, and 1, out of a vertical position and at any necessary angle to the cutting edge of the rotatory disk skiving-knife A¹⁷, as shown in Figs. 2, 3, and 1. 100

Attention is called to the flange upon the feeding device A¹⁶, (shown in detail in Fig. 4 under Fig. 1,) which flange extends out from the nearest side of said feeding device. Attention is also called to this flange in Fig. 2 105 on the left-hand side of said feeding device. Attention is again called to this flange in Fig. 3. The upper end of the lever A¹⁵ is grooved and fits upon the flange of the feeding device A¹⁶, but may be moved or slipped upon said flange. Fast to the upper end of the lever A¹⁵ is a hook, to which one end of the coil-spring A¹⁸ is shown secured, the other end of the coil-spring A¹⁸ being shown secured to a screw shown in the support A¹⁹, shown secured to the bracket A', which spring is shown expanded or stretched beyond its normal length, exerting force upon the lever A¹⁵. The lower end of the lever A¹⁵ is shown forked and fitted upon the roll A¹⁴, which roll is 110 shown movably secured upon the stud A¹³ (shown also in detail in Fig. 10 under Fig. 3) and is prevented from coming off of said stud by the hexagon nut shown on said screw in Fig. 3. When the rod A⁶ (shown at the bottom of Fig. 3 and in detail in Fig. 10) is moved toward the right in practice by the cam A⁵, as hereinabove described, thereby carrying the roll A¹⁴, the lever A¹⁵, shown connected with said roll, is moved toward the 115 120 125 130

right by said roll, and the flange of the feeding device A¹⁶ is gripped by said lever and the lower part of said feeding device is carried toward the right, and the upper part of said feeding device is thereby carried toward the left in order to move the leather toward the left or toward the rotatory disk skiving-knife A¹⁷ and the folding and rubbing device A⁴, and the coil-spring A¹⁸, shown secured to the hook shown in the lever A¹⁵ and to the screw shown in the bracket A¹⁹, is expanded or stretched beyond its normal length, and the spring A⁹, shown in Fig. 3 secured to the screw shown in the sleeve A¹² shown on the rod A⁸ and shown secured to the screw shown in the bracket A', is also expanded, which spring A⁹ moves the rod A⁸ toward the left in practice, the cam A⁵ permitting thereby moving the lower end of the lever A¹⁵ toward the left, allowing the spring A¹⁸, shown secured to the hook in the lever A¹⁵, to move or slip the lever A¹⁵ toward the left upon the flange of the feeding device A¹⁶, while the feeding device A¹⁶ is prevented from being moved by this movement by the cylindrical chock or "trig" A⁴⁶, forced down in the V-shaped opening (shown in Fig. 3 by dotted lines) between the face of the feeding device A¹⁶ and the back of the slot in the device A²⁷ (shown, also by dotted lines) by the spring A⁴⁷, shown secured to the device A²⁷ by the screw A⁴⁸.

In Fig. 2 the bottom part of the presser-foot B is shown above the feeding device A¹⁶ and near thereto. The screw having the hexagon head shown in front of the presser-foot B is inserted in a slot shown by dotted lines in the presser-foot under the hexagon head and is threaded in another piece in the manner shown in Fig. 3, clamping the presser-foot B to the other piece by said screw, as is shown in Fig. 3, and leaving the presser-foot adjustable to the right and left on the piece to which it is secured, as is plain by this construction in Fig. 2. The piece to which the presser-foot B is thus secured thereby becomes a part of the presser-foot B. This part to which the presser-foot B is thus secured is movably secured to the arm B²² (shown in Figs. 2 and 3) by the two screws shown in Fig. 2 immediately above the hexagon screw, which screws extend through the slot in the upper part of the presser-foot B (shown by the dotted lines under the round heads of said screws) and are threaded in the arm B²², which is rigidly secured to the frame A², affording an adjustment of the presser-foot up and down. Therefore it is plain by the devices shown in Fig. 2 and the description thereof that this presser-foot is rigidly secured, but is manually adjustable toward the right and left and is also adjustable up and down.

The presser-bar B²¹ is shown in Figs. 1, 2, 65 and 3 movably secured in the arm B²². Upon

the presser-bar B²¹, between the bearings in which it is movably secured, a collar is shown rigidly secured to said presser-bar B²¹. Resting upon this collar the end of the long flat spring B²³ is shown, which spring presses the 70 presser-bar B²¹ downward with great force as far as the knurled nut on the top of the presser-bar B²¹ permits. Said flat spring B²³ is secured to the arm B²¹ by the first screw (shown by dotted lines in Fig. 2) at the left 75 from the screw B¹⁰ in the arm B²², and said flat spring is forced down upon the collar of the presser-bar B²¹, thereby forcing the presser-bar downward by the second screw at the left from the screw B¹⁰ in the arm B²², 80 (shown also by dotted lines in Fig. 2,) which screw is shown knurled in Fig. 3 and extends through a slot in the spring B²³ and is threaded into the frame A², by which screw the amount of pressure upon the presser-bar B²¹ 85 may be manually governed. Upon the bottom of the presser-bar B²¹ the presser B²⁰ is shown in Figs. 2 and 3 rigidly secured, which presser B²⁰ is normally held and yieldingly supported at such an elevation above the 90 device A⁴ on account of the above-described devices that the skived part of the leather before it is folded may be moved under the presser B²⁰ without binding the leather; but the folded part of the leather being thicker 95 than the skived part of the leather is forced against said presser B²⁰ in practice and rubbed by the highest portion of the operative part of the device A⁴ at proper times. When the feeding device A¹⁶ is moved in 100 practice intermittently or little by little, as hereinabove described, the part of leather near the edge of the leather is thereby moved intermittently between the presser-foot B and the feeding device A¹⁶ and is moved intermittently against the cutting edge of the 105 rotatory disk skiving-knife A¹⁷ at an angle to said cutting edge of said rotatory disk skiving-knife by said feeding device, and said leather is skived by said skiving-knife little 110 by little near the edge of said leather and shaped like a wedge on account of the intermittent movement imparted to the leather by said feeding device and is intermittently moved up on the device A⁴ for folding and 115 rubbing the skived part of the leather, the body of the leather being toward the left, and the skived part is slit and folded, as and by devices hereinafter described, as it is thus passing, and the shaving cut from said leather as 120 it is thus passing falls upon a sheet-iron chute of common construction, which chute is secured to the frame A² and is adapted to prevent the shavings from getting into the operative mechanism of the machine. The 125 position of one side of this chute is indicated at the left-hand side of Fig. 1 by a dotted line outside of the frame A² near to said frame and extending parallel with said frame, said dotted line passing through the heating de- 130

vice D¹⁴, and the other two sides of said chute are indicated by two dotted lines very near together. This chute is also shown in other figures; but no reference character is placed 5 thereon, because reference to the chute is not considered necessary, as nothing new is claimed in the construction thereof and because the chute is not a part of the operative mechanism whereupon the unitary result of 10 the invention is accomplished, the use of said chute being wholly to prevent the shavings from falling into the operative mechanism of the machine.

Having shown and described the mechanism comprising the rotatory disk skiving-knife A¹⁷ and the feeding device A¹⁶ yielding-supported and the means whereupon the feeding device A¹⁶ is automatically moved intermittently little by little in order 15 to move the leather little by little intermittently against the cutting edge of said rotatory disk skiving-knife A¹⁷ and having also described the general shape and construction 20 of the device A⁴ for folding the skived part of the leather and for rubbing the folded 25 part of the leather from the folded edge inward and set forth the operation of the feeding device A¹⁶ and the rotatory disk skiving-knife A¹⁷ and set forth the result 30 accomplished on account of said skiving-knife and feeding device, attention is called to the specific construction and novel features of 35 the device whereupon the skived part of the leather is folded and rubbed from the folded edge of the leather inward. In Fig. 3 this device A⁴ is shown in side elevation. In Fig. 1 the device A⁴ is shown in plan and is inclosed by the largest circular line in the view. The next to the largest circular line indicates the 40 top of the bevel. (Shown in side elevation in Fig. 3.) Attention is particularly called to this bevel, the device itself being made thick for strength and beveled like a wedge. It should be fully understood that, as it is 45 hereinabove described, this device A⁴ is rotatable and that the direction of its movement is from the skived edge of the leather inward at about right angles to said skived edge, and it should be fully realized that this device A⁴, 50 made thick for strength and beveled for utility and recessed as and for the purpose hereinafter described and adapted to be rotated and moved from the skived edge inward, is regarded as the chief device of this invention. In actual construction the operative 55 part of the device A⁴, (shown in Figs. 1, 2, 3, and 15,) or, in other words, that part of the device A⁴ which contributes in the production of the folded edge by acting upon the leather, 60 is designed to be irregular, or, in other words, some portions of the operative part of the device A⁴ are designed to be higher than other portions of said operative part. The operative part of the device A⁴ is shown recessed 65 clear through the device A⁴ from the inclined

portion B¹⁹ of the operative part of the device A⁴ to the inclined portion of the operative part of the device A⁴, (indicated by the first reference character Z at the left of the reference character B¹⁹,) because the recess shown 70 as extending clear through the device A⁴ shows the operativeness of the invention better than it would if it were shown as not extending clear through the device A⁴, and besides this recess another portion of said operative part of the device A⁴ is shown recessed 75 from the inclined portion indicated by the reference character Z to the inclined portion thereof indicated by the second reference character Z near thereto, which recess Z is 80 not shown as extending clear through the device A⁴. Therefore it is shown by Figs. 1, 2, 3, and 15 that said operative part of the device A⁴ is recessed at various places to various depths and also that said operative 85 part of the device A⁴ comprises a surface some parts of which are higher than other parts. This device is not only a folding and rubbing device, but it is also a cementing device, or, in other words, a device for depositing cement upon the skived surface of the leather before it is folded, as will hereinafter appear. Upon the horizontal part of the recessed portion Z Z of the operative part of the device A⁴ cement is mechanically deposited in 90 practice as and by devices hereinafter described and is deposited upon the skived surface of the leather before it is folded in practice by said recessed portion Z Z as and by devices hereinafter described. The reason 95 why the portion Z Z of the operative part of the device A⁴ is made lower than other portions of said operative part is that if it were not so the cement would be distributed over the surface of the highest portion of the operative part of the folding and rubbing device A⁴, or, in other words, upon that part which rubs the folded part of the leather after it is 100 folded, and this is undesirable; but on account of the portion Z Z of the operative part of the device A⁴, upon which cement is deposited in practice as and by devices herein- 105 after described, being made lower than other portions of the operative part of the folding and rubbing device A⁴ cement is deposited in 110 practice upon the skived surface of the leather by said recessed portion Z Z of the operative part of the device A⁴ before the skived part of the leather is folded, thereby 115 enabling the highest portion of said operative part of said folding and rubbing device A⁴ to rub in practice the opposite side of the leather from the side on which cement is deposited, thereby preventing cement from being distributed upon said highest portion. 120 Therefore the operative part of the device A⁴, comprising recessed portions and a surface some parts of which are higher than other parts, is a distinct novel feature of this 125 invention. 130

Having shown and described that the device A⁴ for folding and rubbing the skived part of the leather is also a cementing device for depositing cement upon the skived part of the leather before it is folded and stated that cement is deposited in practice upon a recessed portion of the operative part of the device A⁴ for folding and rubbing the skived part of the leather, as and by devices herein-
10 after described, and that cement is rubbed in practice by said cementing device upon the skived part of the leather, attention is called to the description of the receptacle in which cement is kept and the devices whereupon cement is automatically taken in practice from said cement-receptacle and deposited upon said recessed portion of said operative part of said device A⁴. The cement-receptacle C (shown in detail in Fig. 13) is in practice manu-
15 ally filled with cement. Two projections or legs are shown upon the front side of said receptacle, and a round hole is shown through each projection or leg. Said cement-receptacle C is secured to the frame A², as shown in Figs. 1 and 3, by screws (shown by dotted lines) extending through said holes in said pro-
20 jections or legs and threaded into the frame A², and said receptacle is also shown secured to the bracket A' by two flat-head screws (shown at the extreme left in Fig. 3) extending through the bracket A' and threaded into the bottom of said receptacle. The shaft C' is shown journaled in said cement-receptacle and extends through said cement. Fast
25 upon said shaft is the cement-wheel C², shown projecting above the top of the cover of said receptacle. Movable secured to said shaft C' is shown the pawl-carrier C³. A spring C⁴ is shown fast to said receptacle and
30 bears against said pawl-carrier C³ and normally forces said pawl-carrier C³ against the screw C⁵, shown fast in said receptacle.) Fast in said pawl-carrier C³ is shown a piece of rawhide C⁶. The pawl C⁷ is loose upon
35 the screw C⁸, which screw is shown fast in said pawl-carrier. The end of the pawl C⁷ is shown held in contact with the ratchet C⁹ by the spring C¹⁰, shown fast to the screw C¹¹, shown in said pawl, and the screw C¹², shown
40 in said pawl-carrier, and said ratchet is shown secured to the shaft C'. A device or striker C¹³ is shown in Figs. 9 and 1 secured to and adapted to be carried by said device A⁴. It is plain by Fig. 9, in which a section of said device A⁴ is shown, that the device or striker C¹³ is carried by the device A⁴ into contact with the rawhide C⁶, (shown in Fig. 13,) fast in said pawl-carrier C³ every time said device A⁴ is rotated. It will be observed that said
45 pawl-carrier is thereby moved a short distance in one direction by said device or striker every time the rawhide C⁶, fast in said pawl-carrier, is struck thereby, thereby forcing the pawl C⁷, carried by said pawl-carrier C³, to engage and turn the ratchet C⁹, the
50 shaft C', secured thereto, and the cement-wheel C², fast to said shaft, intermittently or little by little, thereby taking cement out of said receptacle on the face of said cement-wheel C² at every revolution of the device A⁴, the spring C⁴ moving the pawl-carrier C³ in the opposite direction from the direction in which it is moved by the striker C¹³ every time it is moved by the device or striker C¹³. After cement is in practice thus automatically taken out of said receptacle upon the face of said cement-wheel C² the cement is mechanically taken from said cement-wheel and is mechanically deposited upon the recessed portion Z Z of the operative part of said device A⁴ for rubbing cement upon the skived surface of the leather, which portion Z Z is in practice passing by said cement-wheel at about the same time that cement is taken out of said receptacle on account of devices de-
55 scribed as follows: The device A⁴ is shown in Figs. 1, 2, 3, 14, and 15. The cam C¹⁷ is shown upon the top of said device A⁴, secured to said device A⁴. Said cam C¹⁷ is covered with a cover C¹⁸. (Shown in Figs. 2, 3, 14, 15, and 16.) Said cover C¹⁸ is shown secured to the bracket C¹⁹ by the screws C²⁰ and C²¹. (Shown in the upper part of Figs. 1 and 14 and also near the left-hand upper corner of Fig. 3.) Said cover C¹⁸ is also shown secured to the brackets C²² and C²³ by the screws C²⁴, C²⁵, C²⁶, and C²⁷, as shown in Figs. 1, 14, and 16. These brackets are secured to the cement-receptacle C, as is plain by Figs. 1, 14, and 16. There is a part C²⁸ (shown in Fig. 2) fast to said cover C¹⁸ that extends toward the right. Said part is shown fast upon the frame A². Thus it is plain that said cover C¹⁸ is supported at four different places. Every time that said device A⁴ is rotated said cam C¹⁷, (shown in Figs. 1, 2, 3, 14, and 15,) fast to said device A⁴, is rotated. The cement-brush bar C²⁹, shown mounted in the ways C³⁰ and C³¹, (shown in Figs. 1, 3, 14, 15, and 16,) is shown held against the cam C¹⁷ by the coil-spring C³², shown fast to a pin C³³, shown in said cement-brush bar, and to a pin C³⁴, shown fast in said cover C¹⁸. Therefore it is plain that said cement-brush bar C²⁹ is moved in practice in one direction by said cam C¹⁷ and in the opposite direction by said coil-spring C³². In Figs. 1, 3, 14, and 15 the cement-brush C³⁵ is shown bearing upon the cement-wheel C² in the position it is in practice taking cement from said cement-wheel. It is plain by the shape of said cam C¹⁷ (shown in Fig. 1) that said cement-brush is moved in practice from the position shown in said figures to the recessed portion Z Z of the operative part of said device A⁴, hereinabove described, which recessed portion Z Z is shown in Figs. 1 and 15, and that cement is taken in practice from said cement-wheel C² by said cement-brush C³⁵ and deposited upon said recessed portion Z Z of said operative

part of said device A⁴. The construction of the cement-brush C³⁵ is shown in Fig. 17. Said brush is made of bristles by pulling them double into the hole in said brush-bar by the wire C³⁶, and the end of the wire C³⁶ is secured by the screw C³⁷, thereby securing the bristles in said brush-bar; but the device for taking cement off from said cement-wheel C² is not restricted to this form, but may be any device suitable for the purpose for which this brush is used. I believe that such devices have not been heretofore devised whereupon cement taken out from a cement-receptacle is then taken and deposited upon the skived 15 surface of a piece of leather and I also believe that such means have not been combined with operative parts of skiving-machines or skiving and folding machines and have not heretofore contributed in the production of a folded edge, and therefore I believe that the devices employed in this machine, whereupon cement is taken from said cement-wheel and deposited upon the skived 20 surface of the leather, form a novel combination of devices comprised in this invention, which combination contributes to the production of the unitary result of the machine—viz., a folded edge.

The thumb-screw C³⁸ (shown at the left-hand lower corner of Fig. 3 and shown also in Fig. 1) extends through a hole in the frame A², fitting loosely in said hole, the head of said screw bearing against the outer side of said frame and a collar fast to said screw bearing 30 against the inner side of said frame, said screw being also threaded into the bottom of the adjustable knife-shaft support A²², (shown in Figs. 1 and 2,) which adjustable knife-shaft support comprises the two journal-bearings in which the skiving-knife A²⁰ is 35 rotatably secured. Said adjustable knife-support is held firmly upon the bottom of the frame A² by the hand-screw C³⁹, (shown in Figs. 1 and 2,) which hand-screw is shown 40 threaded upon a screw, (shown in Figs. 1 and 2,) which screw extends through a hole in the bottom of the frame A² and through a slot (shown in Fig. 1) in said adjustable knife-shaft support, and when said rotatory disk 45 skiving-knife A¹⁷ is worn so small that the cutting edge thereof is not in the proper relative position with the edge of the operative part of the device A⁴ the adjustable knife-shaft support A²² may be loosened on the 50 frame A² by said hand-screw, and the knife-shaft support, with the knife-shaft A²⁰ mounted therein, and the rotatory disk skiving-knife A¹⁷, secured to said shaft, may be 55 manually forced forward in practice by said thumb-screw C³⁸ until the cutting edge of said skiving-knife A¹⁷ is in the proper position, and then said knife-shaft support A²² may be again firmly fixed or secured to the frame A² by said hand-screw. It should be understood 60 that the means whereupon said skiv-

ing-knife may be thus moved into position after it is worn so small that it is out of proper relative position with the edge of said operative part of said device A⁴ for folding and rubbing is also a novel feature of this invention. 70

There are operative devices in this machine—viz., devices whereupon the slitting of the skived part of the leather at about right angles to the skived edge of the leather is accomplished—which contribute to the unitary result attained by the machine—viz., a folded edge—which devices have not been heretofore described; but as the nature of the entire combination of devices, or this machine, is 75 such that a description of the operative devices referred would not be fully comprehensive except they be described in combination with other operative parts after due deliberation it has been deemed best that they 80 be described in the operation of the machine, which is as follows: The leather is moved about one-eighth of an inch, in the manner hereinabove described, by the feeding device A¹⁶, operated by devices hereinabove described against the skiving-knife A¹⁷, and is thereby skived a short distance, or about one-eighth of an inch, and the device A⁴ is so timed with the devices whereupon the feeding device is moved that the leather is moved in 85 upon said recessed portion Z Z (shown in Figs. 1, 2, and 15) and the cam-surface A²⁵ on the wheel A³ (shown in Fig. 3) is forced into contact with the roll A²³, (shown in Figs. 1 and 2,) which roll is movably secured to the 90 screw A²⁴, which screw is fast in the lever B', (shown in Figs. 1 and 2,) thereby moving the lever B' fast to one end of the shaft B² and also shown in Fig. 1, thereby turning the shaft B² in the bracket B³, (shown in Fig. 1,) 95 which bracket is secured to the frame A², thereby moving the lever B⁴, (shown in Fig. 2,) fast to the other end of the shaft B² and also shown in Fig. 1, the reference character thereon being near the pivotal point of the 100 lever B⁸ in Fig. 1, in such a manner as to move the link B⁵, (shown in Fig. 2,) pivoted to the lever B⁴ by the screw B⁶, upward against the power of the spring B⁷, secured to a screw in the arm B²² and to a screw in the 105 link B⁵, and moving the right-hand end of the lever B⁸, pivoted to the link B⁵ by the screw B⁹, upward upon the pivot B¹⁰, fast in the arm B²², thereby moving the left-hand end of the lever B⁸ downward and carrying the link 110 B¹¹, pivoted to the lever B⁸ by the screw B¹², and the bracket B¹³, pivoted to the link B¹¹ by the screw B¹⁴, and the knife-bar B¹⁵, movably secured to the arm B²² and rigidly secured to the bracket B¹³, downward, thereby 115 carrying the bending device or spring B¹⁸, shaped somewhat like the letter J and secured to the lower part of the knife-bar B¹⁵, the lower end of which bending device is shown in Fig. 2 by dotted lines behind the knife B¹⁶ down- 120

51

ward, the thickness and width of the lower end of which bending device are shown by dotted lines in Fig. 3, thereby pressing the skived part of the leather down upon the recessed portion Z Z of the operative part of the device A⁴, which bending device B¹⁸ is thereby forced to yield or bend, and the knife B¹⁶, (shown in Figs. 2 and 3,) the lower end of which knife is beveled like a chisel and sharp, which knife is fast to the lower end of the knife-bar B¹⁵, is forced by said knife-bar down upon the skived part of the leather, one side and cutting edge of said knife shearing past and rubbing the shearing device or block B¹⁷, rigidly secured to the frame A² and shown in Fig. 2, and the other side of said knife almost rubbing against the periphery of the moving device A⁴, thereby cutting a slit about one-eighth of an inch long through the leather and at about right angles to the skived edge, thereby disconnecting the skived part from the part not skived, and the cement deposited upon said recessed portion Z Z of the operative part of the device A⁴ as 25 and by devices hereinabove described is rubbed upon the skived surface of the leather, and the recess or opening in the operative part of the device A⁴, which device is being moved in the direction indicated by the arrow shown thereon, is mechanically carried under the part of the leather upon which the bending device B¹⁸ is pressing, whereupon the skived and slit part of the leather is bent downward by the spring B¹⁸ into said recess or opening and is instantly caught and folded under by the inclined portion B¹⁹ and is rubbed in the direction from the folded edge inward by the highest portion of the operative part of the device A⁴, which device is 35 hot, being heated by the gas device D¹⁴, as hereinafter described, said skived part of the leather being firmly but yieldingly held down upon the highest portion of the operative part of the device A⁴, while the folded part is 40 rubbed by the presser B²⁰, fast to the presser-bar B²¹, (shown in Figs. 2 and 3,) which presser-bar is movably supported in the arm B²² and firmly but yieldingly held down by the spring B²³, (shown in Figs. 1, 2, and 3,) 45 secured to the arm B²² by a slotted screw (shown by dotted lines in Fig. 2) at the left of the pivot-screw B¹⁰ in the arm B²², said spring B²³ being held downward upon a collar, shown secured to the presser-bar B²¹ in Figs. 50 2 and 3, by a thumb-screw, (shown by dotted lines in Fig. 2 at the left of said slotted screw,) said thumb-screw extending through a slot in said spring and threaded into the arm B²². 55

Repetitions of the above-described operation produce a folded edge of a piece of leather that may be thicker, but substantially the same thickness as the leather before it is folded.

Let it be understood that a machine comprising devices whereupon the leather may

be moved and skived, a device whereupon said leather may be split at its edge, a cement-receptacle and means whereupon a proper amount of cement may be taken therefrom and put upon the leather, and means whereupon said leather may be folded and pressed, all devised so that it is possible for them to operate in such proximity on the leather that a folded edge may be produced thereon around short curves, originated wholly with me, and therefore I claim the novel combinations of these devices regardless of how the devices are made.

In order that all the cement that is placed upon the recessed portion Z Z of the operative part of the device A⁴ may be used upon the leather every time said cement is put in practice upon the recessed portion Z Z, as described, the device C¹⁴ is devised. The device C¹⁴, shown movably secured to the cover of said receptacle C by the screw C¹⁵ extending through the slot shown in said device C¹⁴ and threaded into the cover of said receptacle, which device C¹⁴ is also movably connected with the thumb-screw C¹⁶, which extends through and fits loosely in a hole in the device C¹⁴, the body of the thumb-screw bearing against one side of the device C¹⁴, as shown in Fig. 13, and a collar, (shown in Fig. 1,) fast to said thumb-screw, bearing against the other side of the device C¹⁴, may be moved toward or from the cement-wheel C² by the thumb-screw C¹⁸, thereby placing the chisel-shaped end of the device C¹⁴ at a proper distance from the cement-wheel C² to allow the cement-wheel C² to take a specific amount of cement out of the receptacle C, or, in other words, to allow said cement-wheel C² to take cement out of said receptacle just as fast as it is needed upon the leather, whereupon the accumulation of cement upon the recessed portion Z Z of the operative part of the device A⁴ is prevented. It will be observed that this cement-receptacle is so made that it is nearly air-tight in order that the liquid in the cement therein may not evaporate.

It is plain that before the unitary result of this machine—viz., a folded edge—can be produced said skiving-knife A¹⁷ must be ground or sharpened. Therefore the mechanism whereupon said skiving-knife may be mechanically ground or sharpened is a component part of the machine which is the subject of the present application and is shown in the drawings, and is described as follows: In Figs. 2 and 1 the upright shaft D is shown journaled in the bearings D' and D², which bearings are shown fast to the frame A². Shown fast to said shaft D is the emery-wheel-shaft support D⁴, having a handle near which the reference character D⁴ is placed, said emery-wheel-shaft support D⁴ also having two arms, the upper one of which is designated in Figs. 1 and 2 by the reference character D³, and each one of these

arms supports a journal-bearing. (Shown in Fig. 2.) The emery-wheel shaft D⁵ is shown journaled in said journal-bearings of said emery-wheel-shaft support. In said shaft is shown the groove D⁶. Upon said shaft is shown the friction-wheel D⁷. The screw D⁸ is shown screwed tightly into said friction-wheel, and the point of said screw fits loosely in said groove D⁶ in said emery-wheel shaft D⁵. Therefore it is plain that the friction-wheel D⁷ is rotated in practice with said shaft, but is movable vertically upon said shaft. Above said friction-wheel D⁷ and bearing against said friction-wheel and around said shaft D⁵ is shown the coil-spring D⁹, the end of which enters into the collar shown upon the shaft D⁵ above said spring, which collar is shown secured to the shaft D⁵ by a screw, and on the top of said emery-wheel shaft D⁵ the emery-wheel D¹¹ is secured, as shown in Fig. 2. In Fig. 11 said friction-wheel D⁷ is shown in detail, and a ring of rawhide D¹⁰ is shown secured upon the inclined part of said friction-wheel. The grinding of said skiving-knife A¹⁷ may be accomplished by the emery-wheel D¹¹, shown fast to said shaft D⁵, as follows: The handle of said emery-wheel-shaft support D⁴ (shown in Figs. 1 and 2) may be moved in practice by hand, thereby moving the shaft D, (shown in Figs. 2 and 1,) secured to said emery-wheel-shaft support D⁴ and mounted in the journal-bearings D' and D², the emery-wheel shaft D⁵, shown rotatably secured in the journal-bearings of said emery-wheel-shaft support, and all the devices shown secured to said emery-wheel shaft, thereby forcing the inclined rawhide surface D¹⁰ (shown in Fig. 11) of the friction-wheel D⁷ (shown also in Figs. 2 and 40 1) into contact with the inclined surface of the friction-wheel D¹², (shown in Fig. 3 and shown also in Fig. 2,) secured by a screw to the skiving-knife shaft A²⁰, which friction-wheel is rapidly rotated by the skiving-knife shaft A²⁰, to which said skiving-knife A¹⁷ is secured, and thereby forcing the emery-wheel D¹¹, secured upon the top end of said emery-wheel shaft D⁵, against the skiving-knife A¹⁷, near its cutting edge, and thereby forcing the friction-wheel D⁷ upward upon the emery-wheel shaft D⁵ against the force of the coil-spring D⁹, whereupon the friction-wheel D⁷, the emery-wheel shaft D⁵, and the emery-wheel D¹¹ are rotated, thereby grinding said skiving-knife. After said skiving-knife is ground sharp the handle D⁴ should be released, thereby allowing the coil-spring D¹³, (shown by dotted lines near the right-hand lower corner of Fig. 1,) secured to the emery-wheel-shaft support D⁴ and to the inside of the frame A², a part of which spring is also shown in Fig. 2, to pull the emery-wheel-shaft support D⁴, the emery-wheel shaft D⁵, and all the devices secured to said emery-

wheel shaft back in the opposite direction 65 from that in which they are moved by hand and to thereby cause the grinding to immediately cease.

The device A⁴ (shown in Figs. 1, 2, and 3) is heated in practice by the gas device D¹⁴. (Shown in Figs. 1, 2, and 12.) The construction of this gas device is shown in detail in Fig. 12. The tube D¹⁵ is shown broken. If gas were applied directly from a gas jet or tip against the device A⁴ and if it were 70 lighted while thus applied, in a few minutes said device would be covered with lampblack from the smoke caused by the burning gas. To prevent the accumulation of lampblack, the gas device shown in Fig. 2 is employed. The draft of the lighted gas inside of the gas device draws air in at the holes D¹⁶ and D¹⁷ in the bottom of said device in practice, and a blue flame is thereby forced out of the top of said gas device through the hole 85 D¹⁸. This flame is practically free from smoke by which lampblack is accumulated, and therefore little or no lampblack is formed in practice. This gas-burner is not of my invention, but is practically the same as the 90 heating device known as the "Bunsen burner." It is evident that other means for heating said device A⁴ may be employed besides this gas device, and it is also evident that other combustibles may be used 95 besides gas.

Having hereinabove described the accompanying drawings of a machine in which this invention is embodied and having carefully set forth the novel features and combinations of this invention, I claim as follows:

1. In a skiving and folding machine the following combination of instrumentalities, viz: a folding device; means for operating the same; a skiving device comprising a skiving-knife and means whereupon it may be actuated; a feeding device the corrugated part of which is at an angle to the cutting edge of said skiving-knife; a presser-foot near said feeding device; manually-adjustable means, whereupon, said angle may be changed, whereupon the leather may be skived at different angles; and means, whereupon, the feeding device is operated, said instrumentalities being organized in operative relation, and said skiving device being adapted to be operated independently of any other operative part of the machine.

2. In a skiving and folding machine the following combination of instrumentalities, viz: a folding device; means for operating the same; a skiving device comprising a skiving-knife and means whereupon it may be actuated; a feeding device the corrugated part of which is at an angle to the cutting edge of said skiving-knife; a rigid presser-foot secured near to said feeding device; manually-adjustable means by which said angle may be

- changed; means, whereupon the feeding device is yieldingly supported; and means, whereupon the feeding device may be actuated, said instrumentalities being organized 5 in operative relation, and said skiving device being adapted to be actuated independently of any other operative part of the machine.
3. In a skiving and folding machine the following combination of instrumentalities, viz: a folding device; means for operating the same; a skiving device comprising a skiving-knife and means whereupon it may be actuated; a feeding device the corrugated part 10 of which is at an angle to the cutting edge of said skiving-knife; a presser-foot secured near to said feeding device; manually-adjustable means, whereupon, said angle may be changed, to cause the leather to be skived at 15 different angles; means, whereupon, the feeding device is operated; a slitting device whereupon slits are cut in the material at an angle to the edge of the material; and means, whereupon, the slitting device is operated; 20 said instrumentalities being organized in operative relation, and said skiving device being adapted to be operated independently of any other operative part of the machine.
4. In a skiving and folding machine the following combination of instrumentalities, viz: a folding device; means for operating the same; a skiving device comprising a skiving-knife and means whereupon it may be actuated; a feeding device the corrugated 25 part of which is at an angle to the cutting edge of said skiving-knife; a rigid presser-foot secured near to said feeding device; manually-adjustable means by which said angle may be changed; means, whereupon, said feeding device is yieldingly supported; means, whereupon, the feeding device may be actuated; a slitting device whereupon slits are cut in the material at an angle to the edge of the material; and means, whereupon, the slitting 30 device is operated, said instrumentalities being organized in operative relation, and said skiving device being adapted to be operated independently of any other operative part of the machine.
5. In a skiving and folding machine the following combination of instrumentalities, viz: a skiving device; a feeding device; a slitting device; a bending device; a cementing device; a folding and rubbing device; a pressing device; and suitable means whereupon they may be actuated; said instrumentalities being organized in operative relation, and the skiving device being adapted to be actuated independently of any other operative part of 35 the machine.
6. In a skiving and folding machine the following combination of instrumentalities, viz: a folding mechanism; a skiving device; a feeding device; a cementing device; and means whereupon they may be actuated;

said instrumentalities being organized in operative relation, and the skiving device being adapted to be actuated independently of any other operative part of the machine.

7. In a skiving and folding machine the following combination of instrumentalities, viz: a skiving device; a feeding device; a bending device; a folding device; a pressing device; and means whereupon they may be actuated; said instrumentalities being organized in operative relation, and the skiving device being adapted to be actuated independently of any other operative part of the machine.

8. In a skiving and folding machine the following combination of instrumentalities, viz: a skiving device; a feeding device; a slitting device; and means whereupon they may be actuated; said instrumentalities being organized in operative relation, and the skiving device being adapted to be actuated independently of any other operative part of the machine.

9. In a skiving and folding machine the following combination of instrumentalities, viz: a skiving device; a feeding device; a slitting device; a bending device; a folding device; a pressing device; and means whereupon they may be actuated; said instrumentalities being organized in operative relation, and the skiving device being adapted to be actuated independently of any other operative part of the machine.

10. In a machine for making a folded edge the following combination of instrumentalities, viz: means for beveling a piece of leather near its edge; means movable at an angle to the edge of the leather for the purpose of folding the beveled part of said leather; means by which said leather may be moved toward said beveling means and said folding means; said instrumentalities coöperating to make a folded edge of proper length, by repeated action.

11. In a machine for making a folded edge the following combination of instrumentalities, viz: means for beveling a piece of leather near its edge; means in consequence of which the leather is slit through its edge at intervals, said slits extending inward from the edge of the leather toward the body of the leather; means in consequence of which the slit parts of said leather are folded against the body of the leather; and means for moving said leather; said instrumentalities coöperating to make a folded edge of the leather, by repeated action.

12. In a machine for making a folded edge the following combination of instrumentalities, viz: means for beveling a piece of leather near its edge; means in consequence of which the beveled part of the leather is slit through its edge at intervals, said slits extending inward from the edge of the leather toward the body of the leather; and means for presenting

said leather to the beveling means, and the slitting means, said slitting means operating upon the leather, by repeated action.

13. In a machine for making a folded edge the following combination of instrumentalities, viz: means for beveling a piece of leather near its edge; means in consequence of which the leather is slit through its edge at intervals, said slits extending inward from the edge of the leather toward the body of the leather; means for applying cement to said leather; means for folding the slit parts of said leather against the body of the leather; and means for moving said leather; said instrumentalities coöperating to make a folded edge of the leather, by repeated action.

14. In a machine for making a folded edge the following combination of instrumentalities, viz: means for beveling a piece of leather near its edge; means in consequence of which the leather is slit through its edge at intervals, said slits extending inward from the edge of the leather toward the body of the leather; means for applying cement to the leather; means adapted to be moved from the edge of the leather inward and to fold the slit parts of the leather against the body of the leather by its inward movement; and means for moving said leather; said instrumentalities coöperating to make a folded edge of the leather, by repeated action.

15. In a machine for making a folded edge the following combination of instrumentalities, viz: means for beveling a piece of leather near its edge; means for slitting the leather through its edge at intervals, said slits extending inward from the edge of the leather toward the body of the leather; means for folding the beveled and slit parts against the body of the leather; and means for presenting said leather to said beveling means, said slitting means, and said folding means; said instrumentalities coöperating to make a folded edge of the leather, by repeated action.

16. The combination of means for slitting entirely through the edge of a piece of leather at intervals, means movable inward from the edge of the leather for folding the slit parts against the body of the leather, means for forcing the slit parts into such relative position with the means for folding that said slit parts may be folded, and a feeding mechanism.

17. In a machine for making a folded edge the following combination of instrumentalities, viz: means in consequence of which a piece of leather is slit entirely through its edge at intervals, said slits extending from the edge of the leather inward toward the body of the leather; means adapted to be moved from the edge of the leather inward to fold the slit parts of the leather on account of its inward movement; and means for moving the leather; said instrumentalities coöperating to make a folded edge, by repeated action.

18. In a machine for making a folded edge the following combination of instrumentalities, viz: means in consequence of which a piece of leather is slit through its edge at intervals, said slits extending inward from the edge of the leather and toward the body of the leather; a recessed means adapted to be moved in a direction inward from the edge of the leather, and adapted to force the slit parts of the leather against the body of the leather, and to rub said slit parts; means for pressing the leather against said means for folding the leather; and means for moving the leather; said instrumentalities coöperating to make a folded edge, by repeated action.

19. In a machine for making a folded edge the following combination of instrumentalities, viz: means in consequence of which a piece of leather is slit entirely through its edge at intervals, said slits extending inward from the edge of the leather and toward the body of the leather; a device for folding the slit parts against the body of the leather, and for rubbing the leather; means for moving the operative part of said device for folding and rubbing the leather in a direction from the edge of the leather inward thereby folding and rubbing said leather; means in consequence of which the leather is held against said means for folding and rubbing; and means for moving the leather; said instrumentalities coöperating to make a folded edge, by repeated action.

20. In a machine for making a folded edge the following combination of instrumentalities, viz: means whereupon a piece of leather may be slit at intervals through its edge; a folding device rotatably supported; means for turning said folding device in a direction from the edge of the leather inward; and means for moving the leather; said instrumentalities coöperating to make a folded edge, by repeated action.

21. The following combination of instrumentalities, viz: a mechanical movable combined folder, rubber and presser designed and adapted to be moved from the edge of the leather inward to fold, rub and press a part of the leather against the body of the leather on account of its inward movement; and means for moving the leather; said instrumentalities coöperating to make a folded edge, by repeated action.

22. The following combination of instrumentalities, viz: means for beveling a piece of leather near its edge; means for operating said means for beveling the leather; means for slitting the leather at intervals through its edge said slits extending from the edge of the leather inward toward the body of the leather; means for operating said means for slitting; and means for moving the leather toward said means for beveling and said means for slitting.

23. The following combination of instrumentalities, viz: a feeding device adapted to move a piece of leather; a mechanism, whereupon, said feeding device may be actuated; a 5 presser-foot or device secured near to said feeding device; a skiving-knife; a mechanism, whereupon, said skiving-knife may be actuated; a slitting device adapted to cut slits through the edge of the leather at intervals; a 10 mechanism, whereupon, said slitting device may be actuated; and a device against which the cutting edge of said slitting device is actuated in cutting said slits. 70
24. The following combination of instrumentalities, viz: a feeding device adapted to move a piece of leather; a mechanism whereupon said feeding device may be actuated; a presser-foot secured near to said feeding device; means whereupon slits may be cut 15 through the edge of the leather at intervals; a beveled, recessed, disk-shaped device adapted to fold, press and rub leather; a bender device adapted to bend the part of the leather to be folded and press it against the operative 20 part of said beveled, recessed, disk-shaped device; means, whereupon, said beveled, recessed, disk-shaped device may be moved and the operative part of it thereby carried in a direction inward from the edge of the 25 leather; and a suitable presser against which said leather is held while it is pressed and rubbed by said folding, pressing and rubbing device. 90
25. In a machine for making a folded edge 30 the following combination of instrumentalities, viz: means whereupon a piece of leather may be slit at intervals through its edge; a device for folding leather; means for moving said device for folding the leather in a direction from the edge of the leather inward; means for moving the leather; a presser-foot; a cement-receptacle; and suitable means in consequence of which a proper amount of cement is taken from said cement-receptacle 40 and put upon the leather; said instrumentalities coöperating to make a folded edge of proper length, by repeated action. 100
26. The following combination of instrumentalities, viz: means for slitting a piece of 45 leather at intervals at its edge; means for operating said means for slitting; a beveled, recessed, disk-shaped device for folding and rubbing leather; a suitable cement-receptacle; suitable means whereupon a sufficient amount of cement may be automatically 55 taken from said cement-receptacle and put upon the recessed surface of said beveled, recessed, disk-shaped device for folding and rubbing leather; means whereupon said beveled, recessed, disk-shaped device may be turned; means for moving the leather; and a presser-foot; said instrumentalities coöperating to make a folded edge, by repeated action. 115
- 65 27. The following combination of instru- 60
- mentalities, viz: a feeding device adapted to move a piece of leather; a mechanism whereupon said feeding device may be actuated; a presser-foot or device secured near to said feeding device; a skiving-knife adapted to bevel a piece of leather at its edge; mechanism whereupon said skiving-knife may be actuated; means whereupon slits are cut 120 through the edge of the leather at intervals; a beveled, recessed, disk-shaped device adapted to fold, press and rub leather; a suitable cement-receptacle; suitable means whereupon a specific amount of cement is taken 125 130

from said cement-receptacle and put upon the operative part of said beveled, recessed, disk-shaped device; a bender device adapted to bend the skived part of the leather and 5 press it against the recessed portion of said beveled, recessed, disk-shaped device; mechanism whereupon said bender device may be actuated; means whereupon the beveled, recessed, disk-shaped device may be rotated 10 and the operative part of it thereby carried in a direction inward from the edge of the leather thereby rubbing cement upon the leather, and folding pressing and rubbing the leather; and a suitable device against which 15 said leather is held while it is pressed and rubbed by said beveled, recessed, disk-shaped device.

30. The following combination of instrumentalities, viz: a feeding device adapted to 20 move a piece of leather; a mechanism whereupon said feeding device may be actuated; a presser-foot or device secured near to said feeding device; a beveled, recessed, disk-shaped device adapted to fold press and rub 25 leather; a rotatory disk skiving-knife secured near thereto; a knife-shaft secured to said skiving-knife; an adjustable knife-shaft support for rotatably supporting said knife-shaft; means whereupon said adjustable 30 knife-shaft support may be manually moved and secured in another position to change the relative positions of the cutting edge of the knife and the edge of the operative part of said beveled, recessed, disk-shaped device; a 35 mechanism whereupon said rotatory disk skiving-knife may be actuated; means whereupon slits are cut through the edge of the leather at intervals; a bender device adapted to bend the skived part of the leather and 40 press it against the recessed portion of the operative part of said beveled, recessed, disk-shaped device; a mechanism whereupon said bender device may be actuated; means whereupon said beveled, recessed, disk-shaped device 45 may be rotated and the operative part of it thereby carried in a direction inward from the edge of the leather, thereby folding pressing and rubbing said leather; and a suitable yielding presser against which said leather is 50 pressed while it is pressed and rubbed by said beveled, recessed, disk-shaped device.

31. The following combination of instrumentalities, viz: a feeding device adapted to move a piece of leather; a mechanism whereupon 55 said feeding device may be actuated; a presser-foot or device secured near to said feeding device; a beveled, recessed, disk-shaped device adapted to fold press and rub leather; a rotatory disk skiving-knife secured 60 near thereto; a knife-shaft secured to said skiving-knife; an adjustable knife-shaft support for rotatably supporting said knife-shaft; means whereupon said adjustable knife-shaft support may be manually moved 65 and secured in another position to change the

relative positions of the cutting edge of the knife and the edge of the operative part of said beveled, recessed, disk-shaped device; a mechanism whereupon said rotatory disk skiving-knife may be actuated; means whereupon slits are cut through the edge of the leather at intervals; a suitable cement-receptacle; suitable means whereupon a specific amount of cement is taken therefrom and put upon the operative part of said beveled, recessed, disk-shaped device; a bender device adapted to bend the skived part of the leather and press it against the recessed portion of the operative part of said beveled, recessed, disk-shaped device; mechanism 70 whereupon said bender device may be vibrated; means whereupon said beveled, recessed, disk-shaped device may be rotated and the operative part of it thereby carried in a direction inward from the edge of the leather thereby rubbing cement upon the leather and folding pressing and rubbing said leather; and a suitable presser against which the leather is held while it is rubbed by said beveled, recessed, disk-shaped device. 75 80 85 90

32. A machine for making a folded edge comprising means whereupon a piece of leather may be slit at intervals at its edge; and a disk-shaped device for folding the leather; and a circular knife, said circular 95 knife and said disk-shaped device being adapted to be moved from the edge of the leather inward at the same time for the purpose of skiving and folding the leather; means for moving the leather; and a presser-foot; said instrumentalities being adapted to operate upon the material in near proximity and to coöperate to make a folded edge of desirable length. 100

33. A machine for making a folded edge 105 comprising means whereupon a piece of leather may be slit at intervals at its edge; and a device for folding leather; and a knife; said knife and said device for folding being adapted to be moved from the edge of the 110 leather inward at the same time for the purpose of skiving and folding the leather; means for moving the leather; and a presser-foot; said instrumentalities being adapted to operate upon the leather in near proximity 115 and to coöperate to make a folded edge of desirable length. 120

34. In a machine for making a folded edge the following combination of instrumentalities, viz: means for beveling a piece of 120 leather near its edge; means whereupon a piece of leather may be slit at intervals through its edge; means for folding said slit parts so as to make a folded edge; means for moving said leather; and a presser-foot; said 125 instrumentalities coöperating to make a folded edge of proper length, by repeated action.

35. In a machine for making a folded edge the following combination of instrumentalities, viz: means whereupon a piece of 130

leather may be slit entirely through at intervals at its edge; means adapted to be moved from the edge of the leather inward for the purpose of folding the slit parts of the leather against the body of the leather; means for moving the leather; and a presser-foot; said instrumentalities adapted to coöperate to make a folded edge of proper length, by repeated action.

- 5 36. In a machine for making a folded edge the following combination of instrumentalities, viz: means in consequence of which a piece of leather may be slit at intervals through its edge, a disk-shaped folder, means 15 for forcing the slit parts into such relative position with said disk-shaped folder that said slit parts may be folded thereby, and

means for turning said folder combined with a feeding mechanism.

37. In a skiving and folding machine the following combination of instrumentalities, viz: a skiving mechanism comprising a skiving device, a folding mechanism comprising a folding device, and manually - adjustable means in consequence of which the relative 25 positions of the operative part of the skiving device and the operative part of the folding device may be changed.

In testimony whereof I have affixed my signature in presence of two witnesses.

FRANK L. HARMON.
